(57) **CLAIM**

The ornamental design for a battery, as shown and described.

DESCRIPTION

FIG. 1 is a front perspective view of a battery, showing our new design;

FIG. 2 is a rear perspective view thereof;

FIG. 3 is a rear view thereof;

FIG. 4 is a top view thereof;

FIG. 5 is a right side view thereof;

FIG. 6 is a front view thereof;

FIG. 7 is a bottom view thereof; and,

FIG. 8 is a left side view thereof.

The design is shown in solid lines in the drawings. The broken lines in the figures represent portions of the article which form no part of the claimed design.

The relatively light shade lines on the surface portions indicate contour and not surface decorations.
